DESIGN FOR A CONDIMENT SHAKER

Boris Blecher, Philadelphia, Pa.

Application November 1, 1946, Serial No. 134,447

Term of patent 14 years

(Cl. D44—22)

To all whom it may concern:

Be it known that I, Boris Blecher, a citizen of the United States and a resident of Philadelphia, county of Philadelphia, State of Pennsylvania, have invented a new, original, and ornamental Design for a Condiment Shaker, of which the following is a specification, reference being had to the accompanying drawing, forming a part thereof, wherein:

Figures 3 and 4 are elevational views respectively of opposite ends of the condiment shaker; and

I claim:

The ornamental design for a condiment shaker, as shown.

BORIS BLECHER.
